UNITED STATES PATENT OFFICE.

WILLIAM F. PATTON, OF HOPKINSVILLE, KENTUCKY, ASSIGNOR OF TWO-THIRDS TO HARRISON HOPPER AND JOHN YOUNG, BOTH OF SAME PLACE.

DESIGN FOR A BULLETIN-BOARD.

SPECIFICATION forming part of Design No. 20,905, dated June 30, 1891.

Application filed April 15, 1891. Serial No. 389,110. Term of patent 14 years.

To all whom it may concern:

Be it known that I, WILLIAM F. PATTON, a citizen of the United States, residing at Hopkinsville, Christian county, Kentucky, have 5 invented and produced a new and original Design for Bulletin-Boards, of which the following is a specification, reference being had to the accompanying drawing, forming part thereof, and which is an elevation or face view 10 of my invention.

The leading features of my design consist of a central longitudinal panel having a time-table divided by series of circle-figures forming column-lines, three panels on each side of 15 the central panel, a lower panel extending across the board beneath the central panel and side panels, series of circle-figures forming lines across the board within the lower panel, circular figures represented as supported on the circle-figures within the lower panel, three upper panels above the central and side panels, and a clock-face above the central upper panel.

The bulletin-board is represented as a frame 25 of oblong shape having the following features:

A represents a clock-face; B, a central upper panel beneath the clock-face, and B' are upper panels located on opposite sides of the central panel.

C is a central longitudinal panel having a 30 time-table and column-lines of circle-figures dividing the time-table. Three panels D are represented at each side of the central longitudinal panel.

F represents a lower panel extending across 35 the board beneath the central longitudinal panel and the side panels. Within the lower panel are represented series of circle-figures forming lines across the board within the lower panel, and G represents circular figures supported on the circle-figures within the lower panel.

What I claim is—

A design for a bulletin-board, substantially 40 as herein shown and described.

WILLIAM F. PATTON.

In presence of—
E. S. KNIGHT,
THOS. KNIGHT.
